(57) **CLAIM**

The ornamental design for a voltage tester, as shown and described.

DESCRIPTION

FIG. 1 is a top left front side perspective view of a voltage tester having the inventive design;

FIG. 2 is a bottom right front side perspective view of the voltage tester shown in FIG. 1;

FIG. 3 is a front orthogonal view of the voltage tester shown in FIG. 1;

FIG. 4 is a rear orthogonal view of the voltage tester shown in FIG. 1;

FIG. 5 is a left side orthogonal view of the voltage tester shown in FIG. 1;

FIG. 6 is a right side orthogonal view of the voltage tester shown in FIG. 1;

FIG. 7 is a bottom orthogonal view of the voltage tester shown in FIG. 1;

FIG. 8 is a top orthogonal view of the voltage tester shown in FIG. 1;

FIG. 9 is a top left front side perspective view of a voltage tester having the inventive design;

FIG. 10 is a bottom right front side perspective view of the voltage tester shown in FIG. 9;

FIG. 11 is a front orthogonal view of the voltage tester shown in FIG. 9;

FIG. 12 is a rear orthogonal view of the voltage tester shown in FIG. 9;

FIG. 13 is a left side orthogonal view of the voltage tester shown in FIG. 9;

FIG. 14 is a right side orthogonal view of the voltage tester shown in FIG. 9;

FIG. 15 is a bottom orthogonal view of the voltage tester shown in FIG. 9; and,

FIG. 16 is a top orthogonal view of the voltage tester shown in FIG. 9.

The broken lines in the drawings are for illustrative purposes only and form no part of the claimed design. The shading lines in the drawings show contour and are not intended to indicate surface orientation.

1 Claim, 8 Drawing Sheets
